UNITED STATES PATENT OFFICE.

ERNEST WILFORD KNOTTS, OF SHAWNEE, OKLAHOMA.

NECKTIE.

1,208,167.

Specification of Letters Patent. Patented Dec. 12, 1916.

Application filed March 13, 1914. Serial No. 824,380.

To all whom it may concern:

Be it known that I, ERNEST WILFORD KNOTTS, a citizen of the United States, residing at Shawnee, Oklahoma, United States of America, have invented certain new and useful Improvements in Neckties, of which the following is a specification.

This invention relates to neckties of the kind adapted to be tied by the wearer, and has for its object improvements whereby the said tie may be worn in a manner to expose any one of four different patterns, colors or materials of which it is composed so as to produce the same effect as could be obtained by the employment of as many different ties, thereby effecting great economy.

According to this invention a necktie is made up of a suitable number of pieces of material of different color, pattern, texture or the like, so cut and joined together as to form a single necktie.

According to a preferred construction the tie is composed of four pieces of material of different color, pattern or texture, two of which constitute the back and front of one end and the other two the corresponding parts of the other end, the same pieces being joined by sewing or any other suitable well-known means.

When in use with a double collar, the tie can be so tied as to expose only one of the pieces of material at a time; consequently four distinct neckties are combined in one article. Obviously not only the color or pattern but also the nature of the material may

be varied, so that a large range of choice may be presented to users. Furthermore, the shape to which the material is cut, as well as its size, may be varied according to the manner in which the article is to be tied, 40 without departing from the spirit of this invention.

One mode of carrying the invention into practice is illustrated by the accompanying drawing, in which four different pieces of 45 material *a*, *b*, *c*, *d* are sewn together at *e* and along their respective edges. The pieces *a*, *b*, *c*, and *d* may be of different colors, patterns or composed of material of different texture.

50 I claim:

A necktie consisting of a band for tying comprising four pieces of material each of a different color, pattern, texture or the like, said pieces being disposed at the opposite 55 ends of the two sides of the tie and there connected together at their adjacent ends and along their respective edges so that the junction of the said pieces is so located as to cause the adjacent parts of the different 60 pieces to be hidden by the wearer's collar substantially as set forth.

In testimony whereof I have signed my name to this specification in the presence of two subscribing witnesses.

ERNEST WILFORD KNOTTS.
